CAMERA

Ronald A. Emmerling, New City, N.Y., assignor to Key-
stone Division of Berkey Photo, Paramus, N.J.

Filed June 15, 1971, Ser. No. 153,488

Term of patent 14 years

Int. Cl. D16—01

U.S. Cl. D61—1

FIG. 1 is a front elevational view of a camera showing my new design;

FIG. 2 is a top plan view of FIG. 1 as taken from lines 2—2;

FIG. 3 is a left side elevational view of FIG. 1 as taken from lines 3—3;

FIG. 4 is a back elevational view of the camera as taken from lines 4—4 of FIG. 3;

FIG. 5 is a bottom plan view as taken from lines 5—5 of FIG. 4; and

FIG. 6 is a left elevational side view of FIG. 4 as taken from lines 6—6.

I claim:

The ornamental design for a camera, substantially as shown.
